UNITED STATES PATENT OFFICE.

GEORGE S. M. RUTTER, OF CANTON, OHIO.

DESIGN FOR A BASKET.

SPECIFICATION forming part of Design No. 27,932, dated December 7, 1897.

Application filed September 20, 1897. Serial No. 652,387. Term of patent 14 years.

To all whom it may concern:

Be it known that I, GEORGE S. M. RUTTER, a citizen of the United States, and a resident of Canton, in the county of Stark and State of Ohio, have invented and produced a new and original Design for Baskets, of which the following is a specification, reference being had to the accompanying drawings, forming part thereof, in which—

10 Figure 1 is a side elevation. Fig. 2 is a bottom view. Fig. 3 is a vertical section showing a portion of the basket.

As shown in the drawings, the leading or material feature of my design consists of a 15 basket having a rounded lower portion and a cylindrical upper portion and provided with a series of corrugations *a*, extending from the annular rib *b* upward to nearly the top of the basket *A* and terminating at the points *c*. Said 20 corrugations taper from about the points *d* upward. The corrugations *a* below the points *d* are formed substantially parallel or of the

same size. The disk *e* is inclosed by the annular rib *b* and is provided with the cross-ribs *a'*.

The top of the basket *A*, above the points *c*, is formed of the plain smooth surface *f*, located just below the rib *g*, which rib surrounds the basket proper. It will be understood that the corrugations *a* approach each 30 other as they extend toward the annular rib *b*.

Having fully described my invention, what I claim as new, and desire to secure by Letters Patent, is—

The design for a basket, substantially as 35 herein shown and described.

In testimony that I claim the above I have hereunto subscribed my name in the presence of two witnesses.

GEORGE S. M. RUTTER.

Witnesses:

JAMES LEONARD,
F. W. BOND.
